UNITED STATES PATENT OFFICE.

WILLIAM H. B. ALLEN, OF CAMBRIDGE, MASSACHUSETTS, ASSIGNOR TO HIMSELF AND CHARLES L. ALLEN, OF SAME PLACE.

IMPROVEMENT IN WINDOW-BLIND FASTENERS.

Specification forming part of Letters Patent No. **222,435**, dated December 9, 1879; application filed May 6, 1879.

To all whom it may concern:

Be it known that I, WILLIAM H. B. ALLEN, of Cambridge, in the county of Middlesex and State of Massachusetts, have invented a new and Improved Window-Blind Fastener, of which the following is a specification.

My invention consists in a blind or shutter fastener operating to retain the blind open or closed and fitted for convenient manipulation.

I make use of a pivoted catch and lever hung on the stile of the blind, which locks with the hinge-staple to hold the blind in either position.

The construction and operation will be more particularly explained in connection with the accompanying drawings, wherein—

Figure 1 is a perspective view of the fastener applied to a blind in a closed position. Fig. 2 is a top view, the blind being in section on a horizontal line. Fig. 3 is an inverted plan view with the blind open. Fig. 4 is a front view of the fastener detached.

Similar letters of reference indicate corresponding parts.

The fastener will usually be applied for operation in connection with the lower hinge of a blind or shutter.

The blind (represented at A) is hung on hinge-pins that project from staples b, of any usual or desired character.

The fastener B is hung at the outside of the stile a of blind A in a socket-plate, c, that is attached by screws. The fastener consists of a bent lever or arm, d, that passes through the socket of plate c, and is formed at its end next the hinge with a right-angled extension, e, which extends inward at the side of staple b. The outer end of lever d is fitted with a handle, f, that passes between the slats of the blind to the inside, or, in case the blind is not slatted, through an aperture made especially

for it. The fastener is to be operated by this handle f, as hereinafter described.

The extension e, when in the position shown in Fig. 1, lies closely against the side of staple b, thereby serving to prevent the blind turning on its hinges until, by movement of lever d, the extension e is raised high enough to pass over the staple as the blind swings open, which movement may be effected by pressure on handle f.

At the under side, and in the outer portion of the extension e, is a slot or mortise, i, (see Figs. 3 and 4,) which, when the blind is fully opened, drops over the staple b to retain the blind in position, as shown by Fig. 3. The fastener is weighted to fall to its locked position.

The fastener will preferably be made of malleable iron, lacquered or galvanized.

The above-described construction furnishes a blind and shutter fastening of simple and durable construction, which can readily be applied, and may be operated conveniently. No mortising or other cutting of the blind is required, and the fastener is specially adapted for application to blind-hangings of usual character.

Having thus described my invention, I claim as new and desire to secure by Letters Patent—

As an improved blind-fastening, the device B, consisting of a lever, d, having the extension e, mortised at i, the socket-plate c, and handle f, combined for operation in connection with a hinge, substantially as shown and described.

WILLIAM HENRY BURBECK ALLEN.
